GARMENT HANGER

Harrie S. Geer, Watervliet, N. Y.

Application February 9, 1934, Serial No. 710,625

4 Claims. (Cl. 223—92)

The present invention relates to a garment hanger or clothes hanger of either wire or wood construction, and is primarily designed to support ladies' gowns, dresses, and other similar garments.

With the type of coat hangers now widely utilized there is a tendency for the garments to slip off the hanger, particularly in the case of ladies' dresses and evening gowns. Moreover, the hangers usually do not properly support the garments which may be hung upon them, and usually result in their distorting the gowns and making it necessary to press the garment more often.

Various different constructions have been proposed to improve the hangers at present utilized, but as a general rule these constructions include some disadvantageous feature such as the necessity of utilizing hooks and/or clasps, clamps or fasteners for the gowns and dresses, which may catch and tear the garment. Moreover these constructions are usually expensive to manufacture and readily deranged during utilization and they frequently necessitate considerable manipulation by the person placing the garment thereon.

An object of the present invention is to provide an improved garment or clothes hanger, which is universally adapted for women's clothing, and which is particularly adapted for light weight women's frocks and particularly evening gowns, and which is of inexpensive construction and may be utilized to hang garments without difficulty and without the necessity of resorting to undesirable manipulations.

Another object is to provide an improved clothes and garment hanger which will hold the clothes and particularly will hang or support women's dresses and frocks in such a manner as not to distort them and to center them correctly upon the hanger without the shoulder on either side becoming misshapen.

Other objects will appear during the course of the following specification.

In accomplishing the above objects it has been found most satisfactory to provide a stepped arrangement on the downwardly inclined sides of the hanger on both sides of the central hook, which stepped arrangement should preferably be initiated about half-way down the inclined slope on each side of the hanger. Each step preferably extends a distance varying between one-quarter and one-eighth the length of each inclined slope and the floor of the steps may be

straight or curved and preferably are arranged so as to be parallel to the main slope.

The steps are most desirably arranged so as to be very shallow and at the end of the hanger there is an elevated portion which continues the line of the main slope, so that the depressed steps are confined to an intermediate portion of the slope.

The edges of the steps in the preferred construction are arranged substantially perpendicular or re-entrantly to the main slope.

The above and other objects will appear more clearly from the following detailed description, when taken in connection with the accompanying drawing which illustrates a preferred embodiment of the inventive idea.

In the drawing:

Figure 1 is a top perspective view of one embodiment of the invention showing the stepped construction as applied to wooden hangers.

Figure 2 is a side sectional view upon the line 2—2 Figure 1.

Figure 3 is a front view of a modification showing the application of the present invention to a wire frame hanger.

Figure 4 is a fragmentary front view of another modification.

Referring to Figs. 1 and 2 the arcuate-shaped main wooden body 10 (which also may be made of bakelite or other plastic compositions or materials) is provided with a central axial opening 11 through which extends the shank 12 of the wire hook 13. The lower portion of the shank 12 is provided with an enlarged portion 34 which contacts with a flattened portion 35 on the bottom side of the body 10. The upper shank of the hook is formed into the rounded member 14, which as indicated in Fig. 2 may be turned in either direction.

As shown, the main inclined surface 15 for receiving the garments curves downwardly from the hook 13 or shank 12 toward the ends 16 and at a substantial distance away from the shank 12, it is provided with the steps 17 and 18, the bases 19 and 20 of which are parallel to the main slope 15. The continuation of the main slope 15, as indicated at 21, extends to the end portions 16. It will be noted that the steps 17 and 18 are very shallow and that the shoulder portions 31 and 32 are positioned perpendicular to the main arcuate surface 15. At the end of the last step 18 is positioned the ascending shoulder 23.

It will be noted that the lower side of the hanger of Fig. 1 is provided with the flat surface 35 and with the inclined surfaces 24 which extend

toward the ends 16 from the ends of the flat surface 35.

In the preferred construction, as shown in Fig. 1, the steps 17 and 18 occupy an intermediate 5 half to three-quarters of the inclined slope 15 and as a general rule these steps are preferably positioned closer to the end points 16 than they are to the central elevated portion 25 of the main slope.

10 As indicated by the dotted lines 26 and 27 a garment may be very conveniently hung upon these hangers with the inside of the neck being centrally located by the shoulders 31 and with the sleeve portions 27 positioned inside of the 15 shoulders 23.

By hanging the garment in this fashion it will be supported without danger of distortion or slipping off the hanger and at the same time it may be most readily placed upon the hanger 20 without skilfull manipulation and without difficulty.

It will be noted that the hanger whether of 25 wooden or plastic material may be most readily constructed in an inexpensive fashion without difficulty.

When utilized, there is no danger of the clothes being ripped when being taken therefrom or when they are hung together on a rack or in a closet and subjected to lateral or longitudinal 30 stresses.

In Fig. 3 is shown a wire frame embodiment in which similar functioning parts are referred to by the same numerals primed. It will be noted in this figure that the entire frame is formed of 35 one piece or loop of wire and the shank 13' is formed by twisting one end 270 around the other end 28 to form a closed loop. According to this construction, the entire lower reach 35' is straight and horizontal and extends between the end 40 points 16'. It will be noted that the main slope 15'-21' is straight and that the floors 19' and 20' of the steps 17' and 18' are flat. It is apparent that all the various features previously pointed out are also present in this construction 45 of Fig. 3.

The hangers as illustrated in Figs. 1 and 3 preferably have a dimension 29 or 29' of about 16" and have a height 30 or 30' of about 4". The shoulders 31 or 31' usually have a dimension of 50 about 2 1/4".

Fig. 4 shows an alternative construction similar

to Fig. 1 in which the steps 23², 22² and 31² are inclined inwardly so as to form sharp re-entrant angles.

In the construction of Fig. 4 the arcuate main wooden body is provided with a main inclined 5 surface 15² for receiving the garments, not shown, which curves directly toward the end portion 16² and at a substantial distance away from the central hanger element, not shown, it is provided with the recesses 17² and 18², the bases 19² and 10 20² of which are convexed upwardly. The continuation of the main slope 15², as indicated at 21², extends to the end portion 16². It will be noted that the recesses 17² and 18² are also very shallow and that the steps 31² and 22² descend 15 while the step 23² ascends.

What is claimed is:

1. A garment hanger particularly universally adapted for hanging women's dresses, and frocks of variant shoulder sleeve and shoulder strap 20 design with assurance that such dresses and frocks will not slip thereoff, said hanger being provided with an elongated dress shoulder support element and a central hanger element extending upwardly from the central portion of said support element, said support element sloping slightly downwardly from said central hanged element on both sides thereof and both said sides of said support element being provided with a plurality of spaced shoulders forming a plurality of wide- 30 elongated shallow steps, at least two steps on each side of and most adjacent the central hanger element descending away from said central hanger element and at least the last step on each side of the central hanger element and most distant 35 therefrom being ascending, the end steps cooperating with each of the other steps in supporting shoulder parts of garments.

2. The hanger of claim 1 in which the portion between the first and last steps is depressed below the downward slope of the central hanger elements, the last ascending step rising to the level of the slope of said support element.

3. The hanger of claim 1 in which the central hanger element and support element are formed 45 of one piece of wire, the lower ends of the support element being connected by a horizontal wire reach.

4. The hanger of claim 1 in which the bottoms of the shallow steps are convexed upwardly. 50
